UNITED STATES PATENT OFFICE.

DANIEL G. REITZ, OF BERLIN, PENNSYLVANIA.

BOLTING-REEL.

SPECIFICATION forming part of Letters Patent No. 397,937, dated February 19, 1889.

Application filed March 13, 1888. Serial No. 267,117. (No model.)

To all whom it may concern:

Be it known that I, DANIEL G. REITZ, a citizen of the United States, residing at Berlin, in the county of Somerset and State of Pennsylvania, have invented a new and useful Improvement in Bolting-Reels, of which the following is a specification.

My invention relates to an improvement in bolting-reels; and it consists, first, in a reel having a series of helical flutes arranged at a suitable distance within the screen and rotating therewith; and my invention further consists in the peculiar construction and combination of devices that will be more fully set forth hereinafter, and particularly pointed out in the claims.

In the accompanying drawings, Figure 1 is an elevation of a bolting-reel embodying my improvements, parts of the screen and of the cant-boards being removed so as to disclose the interior construction of the apparatus. Fig. 2 is a detail elevation of the reel with the screen removed, partly in section. Fig. 3 is a vertical transverse sectional view taken 25 on the line *y y* of Fig. 1. Fig. 4 is a detailed sectional view of the head of the reel, taken on the line *z z* of Fig. 2.

A represents a vertical rectangular frame or case, which is of the usual construction, is 30 provided with the inclined cant-boards B, and has a pair of conveyer-troughs, C, arranged side by side in its lower portion and extending longitudinally through the same, the central partition, D, of the said conveyer-trough 35 being arranged directly under the center of the space between the lower edges of the cant-boards. The lower edges of the cant-boards are connected at suitable regular distances by transverse cleats E, which are provided 40 on opposite sides with projecting flanges F, and are beveled or inclined in opposite directions on their upper sides.

G represents a series of cut-off drawers or slides, which have their ends inclined at the 45 same angle with the cant-boards, the lower sides of the said cut-off slides being open, and said cut-off slides being provided with grooves H in their sides, which grooves engage the flanges F of the cleats and thereby support 50 the cut-off slides under the cant-boards and enable said slides to be moved transversely, so as to cause them to discharge the material

that falls between the cant-boards into either of the conveyer-troughs at will, as will be readily understood. The inclined ends of the 55 cut-off slides are provided with suitable knobs or handles, I, by means of which the cut-off slides may be readily operated.

The conveyer-troughs are provided with hinged lids or covers K, and have suitable 60 discharge-openings in their lower sides, and in the said conveyer-troughs are arranged the usual worm conveyers, L, the shafts of which project beyond one end of the conveyer-trough and are provided with sprocket- 65 wheels M.

N represents an imperforate body which is cylindrical in shape, and has its outer sides formed by a series of helical flutes, O, which have the convex or curved tangential sides P 70 extending in the direction in which the bolt rotates, and have the concave shoulders R at the inner end, s, of the said concave sides. The said helical flutes have their higher ends at the head of the reel and their lower ends 75 at the discharge end of the reel, as shown in Fig. 2.

At the discharge end of the reel is a circular projecting plate, S, which is provided with discharge-openings, T, which communicate 80 with the discharge end of the flutes, and surrounding the reel, at regular distances apart and at a suitable distance from the sides thereof, are a series of rings, U. The head of the reel is formed by a ring, V, the external diameter of which is equal to the external 85 diameters of the rings U, and said ring V is secured to the proximate end of the cylindrical portion of the reel by means of a series of curved arms, W, the said arms being arranged 90 in the same curved lines with the flutes and communicating with the higher ends of the same, for the purpose to be hereinafter described.

The screen or bolting-cloth X, which is of 95 silk, as is usual in this class of machines, is stretched over the rings S, V, and U, and is secured thereon in the usual manner, and is thus supported at a suitable distance beyond the flutes. The reel is provided with a central longitudinal shaft, Y, which is journaled 100 in suitable bearings at the ends of the case or frame.

Z represents a stationary ring, which is ar-

ranged within the revolving ring V and has its outer edge beveled, as shown, to fit the corresponding bevel on the inner side of ring V. Said ring Z is connected to the inner side 5 of the case or frame at one end of the latter, and is arranged directly opposite the head end of the cylindrical reel.

A' represents the feed-hopper, which is secured on the end of the case or frame in which 10 the head of the reel is arranged, the said hopper being adapted to feed the stock to the head of the reel, as shown.

To one end of the shaft Y is keyed a sprocket- 15 et-wheel, B', which is of somewhat less diameter than the sprocket-wheels M, and is connected thereto by means of an endless sprocket-chain, C'. To the opposite end of the said shaft Y is secured a driving-pulley, D'.

E' represents a vertical dust-board or partition, which is arranged in the frame, and 20 has a central opening, through which the discharge end of the reel extends. The said dust-board or partition is made in separable sections F', whereby said dust-board or partition 25 is adapted to be removed in order to permit access to be attained to the reel when the bolting-cloth is being attached to or removed therefrom.

The operation of my invention is as follows: 30 The reel is rotated in the direction indicated by the arrow in Fig. 3 at the rate of about sixty revolutions a minute, and the stock is fed to the lower side of the screen at the head of the reel by the hopper hereinbefore described. As the reel rotates, the stock is fed into the upper ends of the flutes by the curved arm W, so as to prevent the head of the reel from becoming crowded with the stock, and that portion of the stock which is in the lower 35 side of the screen will be carried by the upwardly-moving side of the screen until it reaches about two-thirds the height of the screen, when the stock will fall from the screen by its own gravity into the flutes. As the flutes 40 containing the stock pass the upper dead-center of the reel, the stock is projected therefrom by centrifugal force against the inner sides of the screen, thereby forcing the flour or finer particles through the screen, while the 45 middlings or coarser particles will fall to the bottom of the screen and be again subjected to the operation just described. Owing to the helical direction of the flutes, the tailings are gradually worked toward the discharge 50 end of the reel, and are finally discharged therefrom through the openings T, as will be readily understood. As the stock moves downward on the inner side of the screen, it is thoroughly agitated by frictional contact 55 with the screen, and this agitation of the stock also assists in the bolting process, the flour or finer particles being thereby discharged continuously from both sides of the reel. It will be observed by reference to Fig. 3 that the 60 stock is in contact with all portions of the revolving screen excepting that portion of

the screen which is directly over the shaft Y, and the stock is evenly distributed throughout the inner side of the screen, so that the screen is exactly counterbalanced, and thus 70 the screen is enabled to be driven with a minimum expenditure of power; and, moreover, the screen is caused to bolt throughout nearly its entire surface, thereby increasing the capacity of the bolting-reel to the maximum extent. Moreover, the comparatively slow rate of speed at which the reel is operated prevents the stock from being dashed against the screen or bolting-cloth with such force as to materially injure the same, and 80 consequently the durability of the bolting-cloth is very greatly enhanced.

The function of the dust-board or partition is to prevent the dust and dirt which is discharged from the reel with the tailings from 85 enveloping the reel and becoming commingled with the material bolted thereby, thus adapting the reel to produce the finest grade of flour.

Having thus described my invention, I 90 claim—

1. The bolting-reel having the imperforate cylindrical portion, the sides of which are formed by a series of helical flutes, P, having the curved convex tangential sides P, extending in the direction in which the reel rotates, and having the concave shoulders R at the inner edges of said convex sides, the convex side of each flute merging into the concave side of the next adjacent flute throughout the 95 series, the said imperforate cylindrical portion being arranged in the center of the reel at a distance from the bolting screen or cloth, substantially as described.

2. The bolting-reel having the imperforate 105 cylindrical portion, the sides of which are formed by a series of helical flutes, P, having the curved convex tangential sides P, extending in the direction in which the reel rotates, and having the concave shoulders R at the 110 inner edges of said convex sides, the convex side of each flute merging into the concave side of the next adjacent flute throughout the series, substantially as specified.

3. The reel having the imperforate cylindrical portion arranged within the screen or bolting-cloth and provided on its sides with the helical flutes having the convex tangential sides P and the concave shoulders R, the ring V, arranged at a distance from the head of 115 the cylindrical portion of the reel and revolving therewith, and the curved arms W, connecting said ring V with the head of the cylindrical portion of the reel, substantially as 120 described.

In testimony that I claim the foregoing as my own I have hereto affixed my signature in presence of two witnesses.
